UNITED STATES PATENT OFFICE

152,003

DESIGN FOR A LIPSTICK CASE OR SIMILAR ARTICLE

William H. Leavin, New York, N. Y., assignor to Hampden Sales Associates, Inc., New York, N. Y.

Application November 7, 1947, Serial No. 142,385

Term of patent 7 years

(Cl. D86—10)

To all whom it may concern:

Be it known that I, William H. Leavin, a citizen of the United States of America, residing in New York, county of New York, and State of New York, have invented a new, original, and ornamental Design for a Lipstick Case or Similar Article, of which the following is a specification, reference being had to the accompanying drawing, forming part thereof.

Fig. 1 is a front perspective view of a lipstick case or similar article, showing my new design.

Fig. 2 is a top plan view.

The design shown on the front of the lipstick case repeats three times around the lipstick case as indicated in Figure 2.

I claim:

The ornamental design for a lipstick case or similar article, substantially as shown and described.

WILLIAM H. LEAVIN.
